UNITED STATES PATENT OFFICE.

AUGUST HOLMQUIST AND WILLIAM A. BJORKLUND, OF HOOPESTON, ILLINOIS, AS-SIGNORS TO SPRAGUE-SELLS CORPORATION, OF HOOPESTON, ILLINOIS, A CORPORATION OF DELAWARE.

FINISHING MACHINE.

Application filed February 14, 1924. Serial No. 692,716.

To all whom it may concern:

Be it known that we, AUGUST HOLMQUIST and WILLIAM A. BJORKLUND, citizens of the United States, residing at Hoopeston, in the 5 county of Vermilion and State of Illinois, have invented new and useful Improvements in Finishing Machines, of which the following is a full, clear, concise, and exact description, reference being had to the accompanying drawing, forming a part of this 10 specification.

My invention relates to improvements in finishing machines and more particularly to machines for preparing the pulp of the 15 tomato, by reducing it to the proper consistency, in the manufacture of ketchup.

While I shall describe my invention in connection with a machine particularly designed to handle tomato pulp for the 20 purpose described, it will nevertheless be understood that the invention is capable of embodiment in whole or in part, in similar and non-analogous arts, and need not be limited to this use solely.

25 The finishing machine disclosed herein is an improvement over the machines disclosed in United States Patent 1,393,949, granted to Harry W. Lowe on October 18, 1921, and in United States Patent 1,454,031, granted 30 to Leland A. Babcock on May 8, 1923, both of which and the present invention have been assigned to the same assignee.

In these prior patents, the machines disclosed are each provided with a revolving 35 brush operating in close proximity to a finely perforated screen or sieve. The pulp is fed so that it will pass between the brush and sieve. The finer portion of the pulp immediately passes through the sieve, while 40 the heavier material containing crushed seeds, pieces of skins, etc., is picked up by the revolving brush and gradually worked up the sides of this sieve where it is discharged from the machine.

45 The object of the present invention is to provide an improved mounting for the brushes, driving mechanism and the sieve, whereby more convenient access may be obtained to the brushes and screen for cleaning or repairing, and a more rigid mounting obtained for the driving mechanism.

In Patent No. 1,454,031, the machine may be opened from the top by means of a pivotally mounted bracket. Upon this bracket, the driving mechanism is positioned. When 55 ever the brushes or sieve require inspection or cleaning, the driving belt must be disconnected. Furthermore, difficulty is encountered in preventing undesirable vibration of this bracket.

According to the teachings of the present invention, the bowl which carries the sieve is pivotally connected and is adapted to swing downwardly when released so that this brush will be exposed for cleaning or repairing 65 from the under side. The brush remains in its operative position during this time. It is, therefore, not necessary to disturb the clearance between the brush and screen. A marked advantage is thereby obtained in 70 that the finished product of the machine remains uniform. This would not always be obtained where the brush had to be adjusted each time. However, I make provision herein for adjusting the brush in cases where 75 necessary, as for instance, when new brushes are inserted.

The novel construction disclosed herein further permits a quick removal of the screen. The screen is likewise novelly constructed, being provided in sections and reinforced, preferably where the sections are joined. Consequently, should but a portion 80 of the screen wear, it will not be necessary to replace the entire screen as was heretofore 85 required. A considerable saving is thereby affected.

I wish to point out that by opening the machine at the bottom, it is possible to clean the brushes with greater facility than when the machine is opened at the top. With the bottom open, the entire interior may be readily flushed with clean water, the brushes being positioned so that their outer surface may be washed in a direction away from the 95 machine.

Other advantages and objects will appear from the following detail description taken in connection with the accompanying drawings, in which:

Figure 1 is a side elevation of a finishing machine embodying my invention, illustrat-

ing the hopper or bowl swung to open position;

Fig. 2 is a top plan view of a machine;

Fig. 3 is a vertical sectional view taken 5 on line 3—3 of Fig. 2, looking in the direction of the arrows;

Fig. 4 is a top plan view of the screen, being partly broken away to illustrate the manner of joining the sections together;

10 Fig. 5 is a side elevation of the same;

Fig. 6 is a horizontal section through the screen, this view being on a smaller scale than Figs. 4 and 5;

15 Fig. 7 is a detail sectional view through the screen at a point where the sections thereof are joined together;

Fig. 8 is also a detail sectional view of the screen taken through the upper portion thereof; and,

20 Fig. 9 is a vertical sectional view of the bottom portion of this screen.

The preferred form of construction as illustrated in the drawings comprises legs 10 upon which is supported a hopper frame 25 11, a revolving brush 12 mounted upon and driven by a center tubular shaft 13, a novel screen construction 14 and a pivotally mounted hopper 15.

The legs 10 may be of any suitable design, 30 but as I have shown them, they consist of a pair of side frame members 16 and 17 connected together by stay rods 18. Upon the upper surface of side frame members 16 and 17, the hopper frame 11 is suitably bolted 35 at the various points designated 18'. As will be seen in Fig. 2, this hopper frame 11 is provided with a transverse bracket 19, which bracket 19 is adapted to have a driving bracket 20 bolted thereon. The outer end 40 of the drive bracket 20 is bifurcated to provide bearings 21 for a drive shaft 22. This drive shaft 22 extends beyond each bearing 21 for receiving pulleys 23. A belt 24 is entrained over these pulleys 23 and a drive 45 pulley 24 splined to the central tubular shaft 13.

At a lower point on this tubular shaft 13 a pair of spaced annular brush driving members 25 and 26 is fixed thereto, and upon these 50 driving members a series of elongated brushes 27 are supported, which brushes are symmetrically arranged about said shaft for cooperation with the conical screen 14 arranged within the bowl 15. As will be seen in Fig. 2, 55 a clearance is provided between the screen 14 and the brushes 27, so that, during the revolving of the brushes, the pulp will not be forced through the screen, but on the other hand, the pulp will be allowed to travel 60 gently over the inner surface thereof to permit the pulpy liquid to run through the perforations and the heavier material containing crushed seeds, pieces of skin, etc., to pass upwardly to an annular channel 28.

65 A refuse sweep 30 is fixed to one of the

brushes 27 and is adapted to move through the annular channel 28 and carry this heavier material of the pulp to the discharge spout 31.

An adjusting wheel 32 is suitably threaded to a sleeve 33 concentrically mounted with respect to the center shaft 13. This adjusting wheel 32 is adapted to raise and lower the two brush driving members 25 and 26, and consequently raise and lower 70 the brushes 27 with respect to the conical screen 14. I have found it advantageous to provide supporting rods 34 between these driving members 26 and 27, as shown in Fig. 1.

The particular construction of screen 14 is novel in the present case. Screen 14 is removably supported within the bowl 15, being loosely seated in a recess 35 formed in an annular ring 36 carried about the upper 80 edge of the bowl 15. Hinged brackets 37, secured both to the bowl 15 and hopper frame 11, permit the bowl to swing downwardly about the point of the hinges so that convenient access to the brushes may be obtained for the purposes of cleaning and repairing the same. The open position of the bowl 15 is shown in Fig. 1.

By referring to Figs. 4 to 9 inclusive, it 90 will be noted that the screen comprises four sections 40, 41, 42 and 43. As is illustrated in detail in Fig. 7, the adjacent edges of, say, sections 41 and 42 are overlapped into an interlocking fold, with a channel member 44 for embracing the folded portions and securing the same together. The channel members 44 are preferably made of a metal which allows the same to be pressed about the fold and to be held in this position 100 without additional securing means. We, however, could employ bolts, or the like, for locking the channel in place, but with the present arrangement the use of bolts is unnecessary.

By referring to Fig. 8, it will be noted 110 that the upper circumferential edge of screen 14 is held clamped between an upper ring 45 and a lower ring 46, these rings being suitably secured together, say, by bolts 47. A similar arrangement is provided for the lower edge of the screen 14. As shown 115 in Fig. 9, a casting 48 comprises the bottom of the screen 14, and about this casting 48 an annular retaining ring 49 is bolted by means of bolts 50. This retaining ring 49 120 clamps the lower edge of the various screen sections against an inclined face 51 formed on the casting 48. Reinforcing rods 52 are employed between the upper and lower edges of the screen 14 to hold the latter rigidly extended. These rods at their upper end thread into suitable bracket members 53 bolted at 54 to the lower clamping member 46. At the lower end the reinforcing rods 125 52 pass through apertured lugs 56 on the 130

annular retaining ring 49. Nuts 57, or other suitable means, may be used for holding these lower ends in the lugs 56.

The material to be treated, such as tomato pulp, is introduced into the machine by depositing the same into a hopper 58, supported by bracket 20, said hopper being arranged to discharge into the upper end of the hollow shaft 13, whence the material 10 travels downwardly in said shaft and is deposited into the lower end of screen 14. At this point, the material is caught up by the brushes 27 and forced thereby through the screen 14. Refuse, such as the heavier portions 15 of tomatoes, is forced by said brushes into the annular passage 28. The refuse collected in said passage is carried by refuse sweep 30 to the discharge opening and passed therefrom through the discharge 20 chute 31 which leads laterally from the machine. The material which is forced through the screen enters the passage or space 59, whence the same passes downwardly and is discharged through the outlet 25 let 60.

It will be noted that the screen 14 is seated within the bowl 15, so that the former may be removed from the underside of the machine, for repairing or cleaning, when 30 the bowl is pivotally swung to its open position, as shown in Fig. 1. The brushes 27 are normally secured to the shaft 13, through the driving members 25 and 26, whereby these parts may assume a unitary 35 relation in that they remain secured to each other and permanently positioned within the frame of the machine, and are not disturbed upon cleaning of the brushes or the screen. In view of this relation, it is preferable to 40 prohibit the upward movement of the screen 14, so that when the bowl 15 is locked in closed position, the screen will also be locked in a rigid position upon the machine, to prevent variance in the clearance between the 45 same and the brushes 27, and furthermore because the invention is directed to a rigid mounting for the driving mechanism, in order to eliminate undue vibration, and also to secure a more efficient driving arrangement. As before explained, the upper annular clamping members 45 and 46 of the 50 screen is seated in a recess 35 formed in the annular member 36 of the bowl. To prevent this upward movement, a flange 64 is formed 55 upon the interior of the hopper frame 11 and extends a distance sufficient to engage the screen 14. This flange 60 cooperates with the annular member 35 to form a recess closed on three sides when the bowl is in 60 closed position. Thus the screen 14 is securely held in position on the machine.

As shown in Figs. 1 and 2, I have provided a pair of cam locking members 61, which are pivotally mounted and adapted 65 to engage the member 36 to hold the bowl

locked in closed position. These cam locks 61 are mounted to operate in a horizontal plane, and are provided with a cam edge 62, which engages a downwardly slanting bevelled side 63 on member 36. 70

From the foregoing it will be seen that I have provided a novelly constructed finishing machine that may be used for reducing tomato pulp to a proper consistency, in the manufacture of ketchup, it being possible 75 however to use other material when the machine can aptly be used therefor and will admit of such use. The pulp feeding mechanism and driving mechanism for the revolving brushes are uniquely combined, and, 80 with the brushes, these parts are arranged so that they may have a substantially rigid mounting. The bowl and screen may be removed without interfering with this mounting, and consequently access to those parts 85 requiring cleaning or repairing may be obtained in a very convenient manner.

Without further elaboration, the foregoing will so fully explain the gist of my invention, that others may, by applying current knowledge, readily adapt the same for use under varying conditions of service, without eliminating certain features which may be properly said to constitute the essential items of novelty involved, which 95 items are intended to be defined and secured to me by the following claims.

I claim:—

1. In a finishing machine, a perforated screen, means for supplying material to said screen, a revolving brush for moving said material over said screen, and a bowl for receiving the material passing through said screen, said bowl being pivotally mounted and permitting access to the interior of said machine from the underside thereof. 100

2. In a finishing machine, a perforated screen, means for supplying material to said screen, a revolving brush for moving said material over said screen, a bowl for receiving the material passing through said screen, and a pivotal mounting for said bowl. 110

3. In a finishing machine, a perforated screen, means for supplying material to said screen, a revolving brush for moving said material over said screen, a bowl for receiving the material passing through said screen, said screen being mounted in said bowl, and a pivotal mounting for said bowl. 115

4. In a finishing machine, a perforated screen, means for supplying material to said screen, a brush for moving said material over said screen, a bowl for receiving the material passing through said screen, said screen being mounted in said bowl, and a pivotal mounting for said bowl whereby said screen and said bowl may be swung from their normally closed position to an open position to provide access to said brush. 120

5. In a finishing machine, a perforated 130

screen, means for supplying material to said screen, a revolving brush for moving said material over said screen, a bowl for receiving the material passing through said screen, a pivotal mounting for said bowl, and a cam lock for holding said bowl in normally closed position.

6. In a finishing machine, a perforated screen, means for supplying material to said screen, said means comprising a combination supply tube and drive shaft rotatably mounted, brushes for forcing the material supplied at the lower end of said tube through said screen, interconnecting members between 15 said combination tube and drive shaft and said brushes, means for adjusting said brushes longitudinally of said shaft whereby the position of said brushes with respect to said screen may be varied, a bowl, said 20 screen mounted in said bowl, and means for pivotally swinging said screen and bowl out of their position adjacent to said brushes.

7. In a finishing machine, a frame, a perforated screen supported on said frame and 25 adapted to have material supplied thereto, a revolving brush for working the material through said screen, means for driving said brush comprising mechanism in driving engagement with said brush and extending 30 thereabove for support on said frame, and means for permitting said screen to be removed from the under side of said frame.

8. In a finishing machine, a frame, a perforated screen supported on said frame and 35 adapted to have material supplied thereto, a revolving brush for working the material through said screen, means for driving said brush comprising mechanism in driving engagement with said brush and extending 40 thereabove for support on said frame, and means for permitting said screen to be removed from the under side of said frame comprising a pivotally mounted bowl supporting said screen.

45 9. In a finishing machine, a frame, a perforated screen, means for removably supporting said screen on said frame, said means comprising a pivotally mounted bowl in which said screen is normally seated.

50 10. In a finishing machine, a frame, a perforated screen, means for removably supporting said screen, said means comprising a bowl and a pivotal mounting for said bowl, said pivotal mounting permitting said bowl 55 to swing downwardly whereby said screen may be removed from the lower end of said machine.

11. In a finishing machine, a frame, a perforated screen, means for removably supporting said screen in rigid relation on said frame, said means including a flange on said frame preventing upward movement of said screen, and a pivotally mounted bowl in which said screen is seated.

65 12. In a finishing machine, a frame, a per-

forated screen, means for removably supporting said screen on said frame, said means including a flange on said frame, and a bowl having a seat for said screen, said flange and said seat normally cooperating 70 to form a recess in which the upper edge of said screen may be held for rigid support on said frame.

13. In a finishing machine, a frame, a perforated screen, means for supplying material to said screen, a revolving brush for working said material through said screen, a bowl for thereafter receiving the material, and provided with a seat to receive said screen and means for preventing the upward removal of said screen from said frame.

14. In a finishing machine, a frame, a perforated screen, means for supplying material to said screen, a revolving brush for 75 working said material through said screen, a bowl for thereafter receiving the material, and means for preventing the upward removal of said screen from said frame, last 80 said means comprising a horizontally extending flange on said frame.

15. In a finishing machine, a frame, a perforated screen, means for removably supporting said screen on said frame whereby said screen may be removed from the under side of said frame, means for feeding material to said screen, a revolving brush for working the material through the screen, driving mechanism for said brush, a bracket for carrying said driving mechanism, said bracket being rigidly fixed to said frame in overhead relation to said screen to permit said driving mechanism to be retained in permanent driving relation with said brush.

16. In a finishing machine, a frame, a perforated screen, means for removably supporting said screen on said frame, means for feeding material to said screen, a revolving brush for working the material through the screen, driving mechanism for said brush, a bracket for carrying said driving mechanism, said bracket being rigidly fixed to said frame in overhead relation to said screen, and means for preventing the upward removal of said screen.

17. In a finishing machine, a frame, a perforated screen, means for removably supporting said screen on said frame, means for feeding material to said screen, a revolving brush for working the material 120 through the screen, driving mechanism for said brush, a bracket for carrying said driving mechanism, said bracket being rigidly fixed to said frame in overhead relation to said screen, and means for preventing the upward removal of said screen, said means comprising an integral horizontally extending flange on said frame.

18. In a finishing machine, a frame, a perforated screen, means for supplying mate- 130

rial to said screen, a revolving brush for working the material through said screen, driving mechanism for said brush, a bracket for carrying said supply means brush and driving mechanism, said bracket being fixed to said frame whereby removal of said supply means brush and driving means is normally prevented, and a pivotally mounted bowl on said frame for supporting said screen and permitting the removal thereof.

19. In a finishing machine, a screen, a plurality of brushes and means for driving said brushes, said means comprising a shaft in the vertical axis of said screen and a pair of driving members concentric with said shaft and engaging said brushes, and rein-

forcing means between said driving members.

20. In a finishing machine, a screen, a plurality of brushes and means for driving 20 said brushes, said means comprising a shaft in the vertical axis of said screen and a pair of driving members concentric with said shaft and engaging said brushes, and reinforcing means between said driving members, said reinforcing means comprising interconnecting rods substantially parallel to the axis of said screen.

In witness whereof, we have hereunto subscribed our names.

AUGUST HOLMQUIST.

WILLIAM A. BJORKLUND.
